UNITED STATES PATENT OFFICE

2,417,373

LAWN MOWER SHARPENER

James S. Morrison, Springfield, and Frank J. Arciszewski, East Longmeadow, Mass.

Application September 7, 1945, Serial No. 614,908

3 Claims. (Cl. 51—249)

1

This invention relates to improvements in lawn-mower sharpeners and is directed more particularly to sharpeners adapted for attachment to a lawn-mower.

The principal objects of the invention are directed to the provision of sharpener adapted for attachment directly to a lawn-mower for sharpening the longitudinally extending blades thereof whereby the flier carrying the blades need not be removed as is customary.

Various novel features of the invention will be observed from the following description of the invention in the form at present preferred.

In the drawings

Fig. 1 is a side elevational view of a lawnmower sharpener embodying the novel features of the invention.

Fig. 2 is a plan view of the sharpener shown in Fig. 1, with the motor omitted, and

Fig. 3 is a partial inverted plan view of the sharpener shown in Figs. 1 and 2.

Referring to the drawings more in detail the invention will be fully described.

In the drawings the sharpener is shown as it is associated with the lawn-mower which as usual has a pair of spaced side frames 2, wheels 4 outside of said frames and a roll 6 rotatable in between the said side frames.

A stationary cutter bar or blade 8 extends between the frames 2 and a rotatable flier member 10 has a plurality of circumferentially spaced blades 12. As is usual the blades are arranged helically so as to coat with the blade 8 with a shearing action.

End members 14 are provided which may be secured to the frames 2 by bolts 16 or the like and a support 18 extends between and is secured in the members 14 by screws 20 or the like.

A slide 22 is movable on the support 18 and a platform 24 having slots 26 is secured to the slide 22 by screws 28 which pass through said slots and engage the member 22. The platform may be secured in adjusted positions relative to the slide 22 while said slide is movable back and forth on the support 18.

An abrasive wheel 30 has a shaft 32 journaled for rotation in bearings 34 carried by the platform 24. The lower portion of the wheel 30 extends through a slot 36 in the platform, as shown.

An electric motor 38 is secured to the platform and the shaft thereof carries a pulley 40 which is connected by a belt 42 to a pulley 44 of the wheel shaft 32 whereby the abrasive wheel is rotated.

A central screw 48 is in screw threaded en-

2

gagement with a boss 49 on the underside of the platform 24. Other members 51 are slideable in spaced bosses 50 and springs 52 on said members 51 are disposed between the outermost bosses 50 and pins 52 of said members 51 to urge the said members 51 inwardly. The members 48 and 51 cooperate to form a guide between which a blade of the lawn-mower is received.

An adjusting screw 54 is in threaded engagement with the platform 24 and a lock screw 56 is provided for engaging and locking the said screw in place.

With the members 14 secured to the side members of a lawn-mower and the support 18 extending therebetween, the platform overlies the rotatable cutter. The screw 54 is adjusted so as to support the platform from the stationary cutter bar 8 so that a blade 12 of the rotatable cutter is disposed between the inner adjacent ends of the guide members 48 and 51.

With the motor 38 in operation the abrasive wheel 30 is rotated so as to act on a blade 12. The platform 24 is moved back and forth along the support 18 so that the wheel 30 traverses the blade 12.

The member 10 of the lawn-mower is free to rotate so that as the platform 24 is moved back and forth the members 48 and 51 between which the blade 12 is disposed swing the blade so that it is held in engagement with the wheel 30.

That is to say while the platform 24 moves back and forth in a straight line the helically arranged edge of the blade 12 to be ground is between the members 48 and 51. They act on the blade to swing the flier 10 so that the abrasive wheel acts on the blade as though it were straight.

The member 48 may be adjusted as desired while the members 51 being spring pressed urge the blade 12 thereagainst so that as the platform is moved back and forth the blade 12 is guided for the action of the abrasive wheel.

Various changes and modifications may be made in the form of the invention without departing from the spirit and scope of the invention.

What it is desired to claim and secure by Letters Patent of the United States is:

1. The combination with a lawn mower having spaced transversely extending end frames and a longitudinally extending stationary cutter bar between said frames with a flier rotatable between said end frames at one side of said cutter bar having circumferentially spaced longitudinally extending helically arranged cutter blades cooperating with said cutter bar of sharpening

apparatus comprising, end members secured to and extending upwardly from said end frames and spaced outwardly from the other side of said cutter bar, a rod fixed to and extending between said end members, a slide swingable on and reciprocable back and forth on said rod longitudinally of the flier, a platform extending over said cutter bar and flier, connections between said slide and one end of said platform whereby the platform and slide are simultaneously movable, guide means on the lower side of said platform for engaging opposite sides of a cutter blade to rotate the flier and maintain an edge of a blade in said guide means as the platform is moved longitudinally, said platform provided with a slot and having bearing means on its upper side, an abrasive wheel rotatable in said bearing means having a peripheral portion extending through said slot for acting on a blade in said guide means, driving means on said platform having operative connection to said wheel for rotating the same, and a screw threadedly engaging said platform having a lower end engaging said cutter bar to swing the platform up and down and adjust the abrasive wheel relative to the blade in said guiding means.

2. The combination with a lawn mower having spaced transversely extending end frames and a longitudinally extending stationary cutter bar between said frames with a flier rotatable between said end frames at one side of said cutter bar having circumferentially spaced longitudinally extending helically arranged cutter blades cooperating with said cutter bar of sharpening apparatus comprising, end members secured to and extending upwardly from said end frames and spaced outwardly from the other side of said cutter bar, a rod fixed to and extending between said end members, a slide swingable on and reciprocable back and forth on said rod longitudinally of the flier, a platform extending over said cutter bar and flier, connections between said slide and one end of said platform whereby the platform and slide are simultaneously movable, guide means on the lower side of said platform for engaging opposite sides of a cutter blade to rotate the flier and maintain an edge of a blade in said guide means as the platform is moved longitudinally, said platform provided with a slot and having bearing means on its upper side, an abrasive wheel rotatable in said bearing means having a peripheral portion extending through said slot for acting on a blade in said guide means, driving means on said platform having operative connection to said wheel for rotating the same, and a screw threadedly engaging said platform having a lower end engaging said cutter bar to swing the platform up and down and adjust the abrasive wheel relative to the blade in said guiding means, said guide means including a lug extending from the lower side of said

platform having a screw member adjustable therein in a direction transverse to the axis of rotation of the flier for engaging one side of a blade and other spaced lugs spaced away from the first named lug having members slidably therein for engaging an opposite side of said blade and spring means acting thereon whereby said members yieldingly urge said blade against said screw member.

3. The combination with a lawn mower having spaced transversely extending end frames and a longitudinally extending stationary cutter bar between said frames with a flier rotatable between said end frames at one side of said cutter bar having circumferentially spaced longitudinally extending helically arranged cutter blades cooperating with said cutter bar of sharpening apparatus comprising, end members secured to and extending upwardly from said end frames and spaced outwardly from the other side of said cutter bar, a rod fixed to and extending between said end members, a slide swingable on and reciprocable back and forth on said rod longitudinally of the flier, a platform extending over said cutter bar and flier, connections between said slide and one end of said platform whereby the platform and slide are simultaneously movable, guide means on the lower side of said platform for engaging opposite sides of a cutter blade to rotate the flier and maintain an edge of a blade in said guide means as the platform is moved longitudinally, said platform provided with a slot and having bearing means on its upper side, an abrasive wheel rotatable in said bearing means having a peripheral portion extending through said slot for acting on a blade in said guide means, driving means on said platform having operative connection to said wheel for rotating the same, and a screw threadedly engaging said platform having a lower end engaging said cutter bar to swing the platform up and down and adjust the abrasive wheel relative to the blade in said guiding means, said connection bolts threadedly engaging said slide extending through slots provided in the platform transversely of the axis of rotation of the flier whereby said platform may be moved back and forth to position said abrasive wheel relative to said flier.
